COMBINATION EGG COOKER AND SERVER
OR THE LIKEAmos L. Jones, Dayton, Wash., and Lillian M.
Wheeler, Philadelphia, Pa.

Application November 29, 1947, Serial No. 142,878

Term of patent 3½ years

(Cl. D44—29)

To all whom it may concern:

Be it known that we, Amos L. Jones and Lillian M. Wheeler, both citizens of the United States of America, said Jones residing at Dayton, in the county of Columbia and State of Washington, and said Wheeler residing at Philadelphia, in the county of Philadelphia and State of Pennsylvania, have invented a new, original, and ornamental Design for a Combination Egg Cooker and Server or the Like, of which the following is a specification, reference being had to the accompanying drawing, forming part thereof.

Figure 1 is an exploded isometric view of the combination egg cooker and server or the like, showing our new design.

Figure 2 is a part sectional, part elevational view of the combination egg cooker and server or the like, with parts assembled, showing our new design.

We claim:

The ornamental design for a combination egg cooker and server or the like, as shown.

AMOS L. JONES.

LILLIAN M. WHEELER.
